UNITED STATES PATENT OFFICE.

ROBERT T. WARRING AND GEORGE W. STULTZ, OF BROOKLYN, NEW YORK.

RADIATOR AIR VALVE.

Application filed February 19, 1926. Serial No. 89,283.

This invention relates to radiator air-valves for steam heating systems.

It is the universal practice in steam heating systems to provide each radiator with an automatic air-valve which will permit the air and vapor pressure in the radiator to be forced therefrom when the steam pressure in the system rises above the pressure of the atmosphere. When the air has been completely driven from the radiator the valve, if properly adjusted, will close under the action of the steam and prevent the steam from escaping into the room. If the steam pressure decreases below that of the atmosphere, however, the valve opens and permits an inrush of air which rapidly condenses the steam, cools the radiator and fills the system with air so that it is necessary, when additional heat is required, to force out the air from the radiator anew, thereby requiring the development of materially higher steam pressure than would be necessary for supplying heat alone.

It has been proposed to provide a ball check valve in addition to the usual relief valve in order to prevent or restrict the admission of air into the radiator when the fire is checked or for any other reason the steam pressure decreases. To prevent the escape of such valve it is necessary to confine it in a casing having ports communicating with the radiator relief valve and with the atmosphere. The ball valve is designed so that when the steam pressure rises it will force the valve from its seat and allow the air to escape. However, if the steam pressure is high there is likelihood of the valve being carried by the out-rushing air, against the outlet port of the casing, completely closing the same or so restricting it as to greatly hinder the escape of air from the system. Another difficulty inherent in the use of a ball check valve for this purpose is the limited area of the valve in contact with the seat and unless the ball and seat are accurately formed leakage of air into the system may occur.

It is not uncommon for the air relief valve and casing to become displaced from the normal vertical position in which it is designed to operate and in the event of such occur-

rence, the ball valve may not return to its seat when it is desired to restrict the admission of air into the radiator but may rest to one side thereof.

One of the objects of this invention is to provide an air relief valve for radiators which will permit the free escape of air from the system but which will effectively prevent the admission of air into the radiator.

Another object is to provide an attachment which may readily be applied to air relief valves now in common use without alteration thereof and which will prevent or materially retard the admission of air into the radiator without hindering the escape of air therefrom under the action of the steam.

A still further object is to provide a valve of the above nature which will have a large area of contact with its seat and which will tightly close the same when made with only the usual accuracy obtained in high speed machines.

Another object is to provide an improved air-valve attachment which is simple in construction, reliable in operation and which is economical to manufacture.

Other objects and advantages will appear as the description proceeds.

In accordance with this invention a check valve is provided enclosed in a casing which may be attached directly to the outlet of the common types of air relief valves now in common use without alteration thereof. The valve is preferably in the form of a light disk loosely mounted in the casing and normally seating on a flat horizontal seat therein so as to close the outlet port of the thermostatic relief valve. An outlet port or vent is provided in the casing or in a cap applied thereto. The construction of the valve and casing is such that when the valve is raised from its seat and forced against the outlet port it will not obstruct the same and a free escape of air will be permitted.

By constructing the check valve in disk form a seat of relatively large area is provided which, due to the condensation of steam and the formation of a film of water thereon, produces a tight seal.

In order that the invention may be more

fully understood reference will be had to the accompanying drawing in which:

Fig. 1 is a side view of a common form of automatic air relief valve showing the present invention, in section, applied thereto;

Fig. 2 is a top perspective view of a preferred form of check valve;

Fig. 3 is an elevation of the valve shown in Fig. 2; and

Fig. 4 is a sectional view of a modified form of valve casing.

In Figure 1 there is shown a radiator section 1, having a common form of air valve 2 attached thereto. The construction of valve 2 is such that when the steam pressure in the system is low the valve is open and the interior of the radiator is in free communication with the atmosphere. When the steam pressure rises above atmospheric pressure the air is forced out of the radiator ahead of the steam until the steam starts to escape at which time the thermostatic relief valve 2 closes and prevents the further escape of the steam. This construction is in common use and forms no part of the present invention.

In order to prevent the re-admission of air into the system I have provided a check valve 3 which is designed to replace the cap which is ordinarily threaded at 4 to the valve 2. However, if desired, the check valve might be embodied in a unitary structure with the valve 2 at the time it is manufactured. The check valve 3 comprises a casing 5 threaded at 4 to the valve 2 and provided with a passage 6 communicating with the outlet port of the valve 2. The passage 6 is enlarged at its upper end to form a chamber 7 in which a disk 8 is retained. A cap 9 provided for the casing 5 has a vent opening 10 therein. The disk 8 normally seats in the bottom 11 of the chamber 7 closing the passage 6 and preventing ingress of air to the radiator. The upper face of the disk is provided with a number of channels 13 which form passages for the air to the opening or vent 10 when the disk is held against the cap 9 by the outflowing air.

It has been found, due to the large surface of contact between the valve disk 8 and the seat 11 and the formation of a film of moisture therebetween, that a tight seal is obtained. However, if desired, a coating of resilient material 12, such as rubber, may be provided on the contacting face of the disk.

By virtue of the exclusion of air from the radiator by the valve 8 when the steam pressure decreases, a partial vacuum is produced in the radiator which, due to the lowering of the pressure in the system, prevents condensation of the steam until the temperature thereof has been reduced materially below the boiling point of water at atmospheric pressure. The reduced pressure is

maintained in the radiator over a considerable period of time and when additional heat is required it is only necessary to generate a moderate steam pressure in the boiler which may be considerably below atmospheric pressure, to cause a circulation of the steam to the radiators.

In Fig. 4 there is shown a modified form of my invention in which the cap 9 is dispensed with and the casing 14 formed with a uniform bore threaded internally. A valve seat 15 is screwed into the casing, the threads of which terminate a short distance from the interior end 16 to form an abutment for the valve seat. A vent 17 is provided in the end 16 of the casing and the disk valve 8 is interposed between the seat 15 and the vent 17.

If desired, instead of providing the channels 13 in the disk 8 they may be formed in the cap 9 or in the end 16 of the casing 14 so as to provide a bypass around the valve. Obviously many other changes may be made without departing from the invention and I do not desire to be limited to the exact construction shown and described.

What is claimed is:

1. A device of the class described, comprising a tubular casing adapted for attachment to a radiator valve, said casing having an interiorly threaded portion adjacent one end thereof, the opposite end of said casing having a wall with a constricted opening therein, a removable valve-seat within said casing, a valve-disk loosely disposed between said valve-seat and said wall, said valve-disk operating to rest upon said valve-seat to close said radiator valve against atmospheric pressure, said valve seat having a contact surface equal in area to at least one-half of the contacting surface of said valve-disk and means to permit the escape of air when said valve-disk is moved against said wall.

2. A device of the class described, comprising a tubular casing adapted for attachment to a radiator valve, said casing having an interiorly threaded portion adjacent one end thereof, the opposite end of said casing having a wall with a constricted opening therein, a removable valve-seat within said casing, a valve-disk loosely disposed between said valve-seat and said wall, said valve-disk operating to rest upon said valve-seat to close said radiator valve against atmospheric pressure, said valve seat having a contact surface equal in area to at least one-half of the contacting surface of said valve-disk, and means associated with said valve-disk to permit the escape of air when said valve-disk is moved against said wall.

3. A combined radiator valve cap and auxiliary valve, comprising a tubular casing, a closure at one end of said casing having a constricted aperture, the opposite end of said casing being open, an interiorly threaded portion adjacent the said open end of said

casing for attaching the auxiliary valve to a radiator valve, a valve-seat comprising a threaded member adapted to be screwed into the threaded end of said casing, a valve-disk 5 loosely disposed between the closed end of the casing and said valve-seat, said valve-disk operating to rest upon said valve-seat to close the valve against atmospheric pressure, said valve seat having a contact surface equal 10 in area to at least one-half of the contacting surface of said valve-disk, and means to permit the escape of air when said valve-disk is moved against said closure.

4. A combined radiator valve cap and auxiliary valve, comprising a tubular casing, a closure at one end of said casing having a constricted aperture, the opposite end of said casing being open, an interiorly threaded portion adjacent the said open end of said

casing for attaching the auxiliary valve to a 20 radiator valve, a valve-seat comprising a threaded member adapted to be screwed into the threaded end of said casing, a valve-disk loosely disposed between the closed end of the casing and said valve-seat, said valve-disk 25 operating to rest upon said valve-seat to close the valve against atmospheric pressure, said valve seat having a contact surface equal in area to at least one-half of the contacting surface of said valve-disk, and means associated with said valve-disk to permit the escape of air when said valve-disk is moved 30 against said closure.

In testimony whereof, we have hereunto subscribed our names this 15th day of Feb. 35 1926.

ROBERT T. WARRING.
GEORGE W. STULTZ.
